SUPPORT FOR FURNITURE

Forest Wilson, Chicago, Ill.

Application August 1, 1955, Serial No. 37,258

Term of patent 3½ years

(Cl. D33—1)

Fig. 1 is a perspective view of a support for furniture embodying my new design;

Fig. 2 is a front elevational view of the support for furniture of Fig. 1; and

Fig. 3 is a side elevational view of the support for furniture of Fig. 1.

I claim:

The ornamental design for a support for furniture, substantially as shown.
